(No Model.)

G. A. FIRNSTEIN.

PUNCH FOR CUTTING OUT SHAPES FROM SHEETS OF PLASTIC MATERIAL.

No. 475,549.

Patented May 24, 1892.

UNITED STATES PATENT OFFICE.

GEORGE A. FIRNSTEIN, OF CINCINNATI, OHIO.

PUNCH FOR CUTTING OUT SHAPES FROM SHEETS OF PLASTIC MATERIAL.

SPECIFICATION forming part of Letters Patent No. 475,549, dated May 24, 1892.

Application filed February 23, 1892. Serial No. 422,335. (No model.)

To all whom it may concern:

Be it known that I, GEORGE A. FIRNSTEIN, a citizen of the United States, residing at Cincinnati, in the county of Hamilton and State 5 of Ohio, have invented certain new and useful Improvements in Punches for Cutting Out Shapes from Sheets of Plastic Materials, of which the following is a specification.

My invention relates to punches for making apertures or for cutting out disks and other shapes from sheets or plates of various materials, and more especially to punches for cutting mass wafers from thin sheets of show-bread used for sacramental purposes, all of 15 which will be fully hereinafter described, and particularly pointed out in the claims.

In the accompanying drawings, Figure 1 is a longitudinal elevation of my device in its preferred form, showing a hand-press with a 20 wafer-sheet therein; Fig. 2, a transverse sectional elevation on line $x-x$, Fig. 1, looking rearward in the direction of the arrow, with the wafer-sheet omitted; Fig. 3, a sectional plan on line $y-y$, Fig. 1; Fig. 4, a broken longitudinal elevation of my device in a modified form; and Fig. 5, a broken sectional plan on line $y-y$, Fig. 4.

A represents the bed-plate or base, B an upright frame or standard supported there- 30 by, and $b b'$ guide arms or bearings project- ing forwardly from standard B.

C represents a handle or lever hinged at its inner end to the upper end of standard B.

D represents a circular punch, whose up- 35 right stock d passes through the guide arms or bearings $b b'$ and is provided with a re- tracting coiled spring d' .

$a a$ represent transverse pins in the punch- stock having their ends projecting slightly 40 therefrom and arranged at the desired dis- tance apart to suit the stroke of the plunger, and thereby obviate unnecessary motion in either direction.

c represents a short pin in the upper bear- 45 ing b , its inner end engaging a groove c' in the punch-stock to prevent the unnecessary turning of the latter, as clearly shown in Fig. 2.

E represents the die having a circular open- 50 ing corresponding, as customary, with the punch in size and contour, and preferably

mounted in a detachable manner by means of countersunk screws e on the bed-plate or base A, perpendicularly and concentrically in line with said punch. The aperture A' (shown 55 in Fig. 2 and in dotted lines, Fig. 1) made in the bed-plate beneath the die is the maximum in size that it is desired or intended to use the press, and the central aperture in the die may be the same size or smaller to suit the 60 size of punch used and the size of blank to be removed from the sheet or plate.

Different-sized punches can obviously be placed in the press to suit the size of die used by simply removing the pins $a a$ and with- 65 drawing the punch down through the large opening A' in the bed-plate.

F represents a horizontal plate, preferably provided with a downward angular bend f at its inner or rear end and an upright angular 70 bend or extension f' at its outer or fore end, as clearly shown in Fig. 1, the inner end being detachably secured by means of screws to the bed-plate to the rear of the die and the outer end similarly secured to the lower guide- 75 arm b' of the standard B. This plate is pro- vided with a large circular opening or aperture F' , concentric with the circular punch and the die and bed-plate openings, but about one-eighth inch larger than the punch, so as 80 to permit a view or observation of the punching process beneath at all times.

The particular function and object of the plate F is to provide means between the punch and die whereby the delicate and frangible 85 sheet of sacramental bread is prevented from rising with the disk or piece removed by the punch and automatically and readily stripped from the punch on its upward stroke without any liability to crack or break said sheet, such 90 as has heretofore been the result when the fingers or other means were used for the purpose. The vertical portion of the rear bend f in the stripper F provides a back-stop or gage for the inner edge of the sheet to rest against in 95 the punching operation. I prefer securing the outer end of the stripper in the manner shown in Fig. 1, for the reason that it stiffens the stripper and effectually prevents any up- 100 ward motion that might possibly affect the operation thereof and cause the sheet to crack or break. This vertical extension f' also pro-

vides a barrier to prevent the accidental insertion of the wafer-sheet above the stripper, and its lower rounded corner serves in a manner to guide the said sheet under the stripper.

In Figs. 4 and 5 I have shown a modified form of stripper, it being a flat plate without any bend whatever therein and detachably secured at its rear end only to the bed-plate, 10 with a cross-bar f^2 intervening and supporting it the proper height above the die. The outer end of this modified form is thus free, and the plate should therefore be stiff enough to resist the upward motion of the plunger 15 and wafer-sheet, the latter being intended to be stripped without breaking, the same as in the preferred form. The cross-bar f^2 also forms a gage similar to the bend f .

To operate the press, the wafer-sheet W is 20 inserted on the die beneath the stripper-plate F . The punch is then depressed by the handle and in its downward motion cuts or removes the wafer or disk from the said sheet and immediately retracts on raising said handle through the expansive action of spring d' . The cut made is sharp and clean, and the sheet carried upward by the punch (as it will be most of the time) on the upstroke of 25 said punch, will be readily stripped, perfectly 30 intact, and unimpaired from the punch and the disks or wafers, and said disks or wafers removed by the punch either drop through the opening in the bed-plate or they may be readily removed from the bottom of said 35 punch should they adhere thereto, the latter being usually the case. It will be seen that the outer corners of the stripper-plate in both forms are rounded off, so as to prevent any 40 breaking or cracking contact therewith of the delicate wafer-sheets.

It is obvious that the punch and the apertures in the stripper, die, and bed-plate could be made in other shapes than circular and

the press used for cutting sheets or plates of other materials, and also that the die could be 45 made permanent with the rest of the parts constant—that is, the punch and the central openings in the die and bed-plate corresponding with each other and the central opening in the stripper slightly larger than the punch, 50 for the purpose stated—without affecting the principle of my invention herein in the least. It is still further obvious that my stripper-plate could be applied with equal facility to power-punches or to hand-punches or presses 55 of other forms, as well as to the construction herein shown and described, and not affect the principle.

I claim—

1. In a punching device, the combination 60 of a punch, a suitable supporting standard or frame therefor, a die, a suitable bed-plate or base for said die, and a stripper-plate having a central opening in a vertical line with said punch and die, and a transverse gage or stop 65 on which such plate is mounted, the gage being mounted in turn on said bed-plate and supporting said stripper-plate so that it projects forwardly between said punch and die, substantially in the manner and for the purpose 70 specified.

2. In a punching device, the combination 75 of a punch, a die, suitable supporting means therefor, a stripper-plate intervening between said punch and die, and a rigid transverse stop or gage constructed at the rear end of said stripper-plate and forming a support for said rear end of the stripper-plate on the bed-plate, substantially as and for the purpose 80 specified.

In testimony of which invention I have hereunto set my hand.

GEORGE A. FIRNSTEIN.
